UNITED STATES PATENT OFFICE

GEORGE C. THOMAS, JR., OF ELIZABETH, NEW JERSEY, ASSIGNOR TO THE THOMAS & BETTS CO., OF ELIZABETH, NEW JERSEY, A CORPORATION OF NEW JERSEY

CABLE CONNECTER

Original application filed January 22, 1924, Serial No. 687,787. Divided and this application filed July 23, 1926. Serial No. 124,332.

This invention relates to cable connectors for anchoring cables to electric fixture boxes and the like, and the present application is a division of my earlier Patent Number 5 1,594,225, of July 27, 1926.

An object of the invention is to produce new and improved cable connectors possessing a new mode of operation and which may employ operating means which is actuated from the inside and outside of a box to establish final anchorage of all parts, i. e. the operating means, which tightens up the parts, may be actuated from both sides of the box wall.

15 15 A further object is however to produce a connector, the operating means of which may be entirely actuated from the inside of the box if the mechanic so desires.

A further object of the invention is to 20 produce a cable connector employing a connector member suitable in size to fit in or through a box hole and so formed and constructed that a part of the box hole edge is exposed directly to a cable received therein so that the cable is in effect exposed against the box hole edge, and the connector is also 25 itself anchored to the box hole edge.

The accompanying drawings illustrate examples of the invention wherein;

30 Figure 1 shows a longitudinal sectional view through the assembled cable, connector and box; and Figure 2 illustrates an inside sectional view as taken on the line 2—2 of Figure 1.

35 Figure 3 shows an outside end elevation of the connector, Figure 4 a side elevation thereof and Figure 5 an inside end elevation.

The remaining views illustrate a modified 40 form of the invention wherein;

Figure 6 shows a longitudinal sectional view of the assembled cable, connector and box; while Figure 7 illustrates an inside 45 cross-sectional view taken on the line 7—7.

Figure 8 shows an outside end view of the modified connector, Figure 9 a longitudinal section, and Figure 10 an inside elevation.

50 Ordinary electric fixture boxes B are provided with holes H for the reception of cable

connectors and the cable C is introduced into the box hole H and anchored there by operation of a connector.

Referring now more particularly to Figure 1 to 5 for description of the subject matter divided out of my former patent application, there is shown a connector member 6, for example in sleeve form and having tool receiving means such as a corrugated end or nut end 7. The sleeve 6 is made 55 with a box wall entry slot 8 formed transversely in the sleeve for the reception of the box hole edge H by which part of said box hole edge is exposed directly to the cable C within the sleeve. The sleeve is also made with a groove 9 to receive two parts, namely, the box hole edge and key plate, but more particularly to receive the edge of the key plate.

60 A key cam plate 11 is made with a cam or curved inclined edge 12 and is adapted to register with the groove 9 in the connector. That edge of the key plate 11 which is opposite to the cam edge 12, is intended to slide against the wall of a box B to thereby press the sleeve connector 6 laterally with respect to the axis of the box hole.

65 In assembling the parts the connector 6 is mounted in the box hole H with the cable placed therein, the parts going together loosely whereupon the key plate 11 is placed between the connector 6 and the box wall so that the flat edge of the plate 11 bears movably on the box wall while the cam edge 12 bears movably in the connector groove 9. The mechanic drives the key plate into position with a tool or pries it with a screw driver thereby forcibly moving or sliding the plate against the connector sleeve to move it laterally with respect to the box hole axis causing a part of the box hole to project through the wall entry slot 8 and grip with considerable force against the cable which serves to simultaneously anchor the cable and the connector in the box hole.

70 The mechanic may also attain final anchorage or final locking position of all parts by grasping the end 7 of the sleeve with a pair of pliers and slightly rocking

- or partially rotating the connector in the box hole and at the same time he wedges or moves the key plate 11 into final place. By slightly rotating the sleeve 6 the gradually inclined cam plate edge 12 is drawn into place so that the key plate is tightened up between the box wall and connector groove 9 by slight rotation of the sleeve 8 to cause the cam edge 12 to climb into place.
- 10 The slot 8 and groove 9 form spaced abutment means to receive the box hole edge into the connector and to guide and retain movably the connector in the box hole during actuation of the parts, i. e. during actuation of the operating means to anchor all parts in rigid relation. Furthermore the abutment means anchors the connector in the box against longitudinal displacement.
- The sliding key plate 11 operates entirely 20 inside the box by driving or forcing it into tight position between the box wall and connector, and thus the fastening function may be accomplished by actuation of parts entirely within the box.
- 25 On the other hand, the nut end 7 may be forcibly turned, if desired, on the outside of the box to aid in drawing or pulling the plate 11 into place between the connector and box wall. As the sleeve 6 is rocked 30 or partially rotated, the mechanic presses the key plate 11 forwardly and the friction of the cam edge 12 against the groove 9 draws the plate in under the connector and forces the connector sidewise in the box 35 hole to grip the cable against the exposed box hole edge.
- Thus the operating means may be actuated either entirely inside the box or both from the inside and outside.
- 40 Referring now to Figures 6 to 10 inclusive showing a modified form of the invention there is shown a sleeve 14 with double opposed entry slots 15 and 16 for the reception of the box hole edge and for reception 45 of an improved key wedge fork. A neck 18 joins the sleeve 14 to an abutment flange 19. The sleeve 14 together with the neck 18 and abutment flange 19 define aforesaid the oppositely related entry slots 15 and 16.
- 50 The modified form of connector therefore embodies a member having a portion, as for example the part 14, which is suitable in size to fit in the box hole with an abutment 19 that limits the distance into which it may 55 be projected, while the connector member is so shaped and formed, as for example by reason of the slots 15 and 16 or other means, that a part of the box wall edge is left directly exposed to the cable.
- 60 An improved key wedge fork embodies a wedge prong having a wedging edge 22 and including a straight guide prong 23 and the two parts are joined by a neck 24. The inside fork opening defined by the opposed prong parts 21 and 23 is sufficiently wide to admit the connector 14 and particularly to admit the neck 18 thereof so that the opposed slots 15 and 16 register with the inner edges of the key prongs 23 and 21.
- In assembling the parts constituting the connector shown in the latter Figures 6 to 10 just described, the connector 14 is inserted loosely in the box hole whereupon the cable C is introduced into the connector. The opposed connector slots 15 and 16 receive a part of the box hole edge and receive the prongs of the key wedge fork. Also the fork 21—23 fits against the wall of the box and thus anchors the connector in the box hole. The edge 22 of the wedge prong 21 grips the cable and is placed between the cable and a wall of the box thus moving the cable laterally with respect to the box hole axis thereby forcing the exposed part of the box hole edge which is opposite the wedging edge 22, against the cable. In other words, the cable is gripped between the edge 22 and box hole edge H.
- At the same time the straight key fork 23 moves into one of the slots of the sleeve 14 to form an abutment against the box wall in opposite relation to the wedge prong 21 to prevent said part 21 from tilting out of place.
- The mechanic taps or drives the key wedge fork 21—23 into position thereby jamming the cable against the inside box hole edge H and causing the cable to be gripped against the box hole edge. At the same time the key fork establishes a firmly keyed and wedging connection with the cable and also the key fork stands behind or at the end of the sleeve 14 thus anchoring it against longitudinal displacement.
- The fact that the prong 23 of the key fork abuts the box wall on the side of the cable opposite the wedge prong 21 means that prong 21 cannot be accidentally displaced outwardly, that is, the edge which bears against the box wall cannot be pried loose 110 because the neck 18 transmits any tilting strain exerted by the wedge 21 upwardly to the prong 23 which in turn braces the entire plate 21—23 against tilting displacement.
- It is to be noted that the abutment flange 19 is large enough to cover over the box hole H and thus form a well closed and well sealed box and cable connection after the parts are assembled.
- This improved connector takes advantage 120 of the fact that the cable is anchored to the exposed box hole edge and the connector is likewise anchored in and over the box hole edge.
- The slots shown in both forms of sleeve 125 connector are simply an example of means by which the box hole edge is exposed and other sleeve forms may be produced for the same purpose. This connector is so formed as to expose the box hole edge and carries 130

- spaced abutments in between which the box hole edge is received to guide and retain movably the connector during operating movement of the parts. The abutments prevent longitudinal displacement and unloosening of the parts after final assembly and final position of all parts are attained.
- What I claim is:
1. Cable and box connecting means comprising, a box provided with a cable and connector receiving hole, a connector member of suitable size to fit into the hole and formed to expose a part of the box hole edge directly to a cable, and including spaced means in between which the box hole edge is received to guide and retain movably the connector during movement of the parts to final fixed position, and operating means on the outside and on the inside of the box including means operable outside the box and including a separate member operable inside the box, by which the connector is forcibly moved laterally with respect to the axis of the box hole to grip the cable between the exposed box hole edge and connector.
  2. Cable and box connecting means comprising, a box provided with a cable and connector receiving hole, a connector member of suitable size to fit into the hole and formed to expose a part of the box hole edge directly to a cable, and including spaced means in between which the box hole edge is received to guide and retain movably the connector during movement of the parts to final fixed position, and operating means on the outside and on the inside of the box including tool receiving means and a separate key plate, by which the member is forcibly moved laterally with respect to the axis of the box hole to grip the cable between the exposed box hole edge and connector.
  3. Cable and box connecting means comprising, a box provided with a cable and connector receiving hole, a sleeve of suitable size to fit into the hole and having an entry slot into which projects a part of the box hole edge to grip directly against the cable, and operating means on the outside and on the inside of the box including a separate wedging means inside the box, by which the member is forcibly moved laterally with respect to the axis of the box hole to grip the cable between the exposed box hole edge and connector.
  4. Cable and box connecting means comprising, a box provided with a cable and connector receiving hole, a sleeve disposed in the hole and having an entry slot through which projects a part of the box hole edge to grip against the cable, and operating means on the inside of the box including a separate wedging means forced between the sleeve and box portion, by which the member is forcibly moved laterally with respect to the axis of the box hole to grip the cable between the exposed box hole edge and connector.
  5. A connector comprising a member suitable in size to fit in a box hole, and formed to expose a part of a box hole edge to a cable, and a separate wedging member adapted to be forced between the connector and the bottom of a box to move the connector laterally with respect to the box hole axis to grip a cable between the exposed box hole edge and connector.
  6. A connector comprising a member suitable in size to fit in a box hole, and formed to expose a part of a box hole edge to a cable, a separate wedging member adapted to be forced between the connector and a box portion to move the connector laterally with respect to the box hole axis to grip a cable between the exposed box hole edge and connector, and means to receive a tool carried on that portion of the connector adapted to be placed outside the box by which the connector may be rotated to aid in drawing the wedging member into place.
  7. A connector comprising a sleeve adapted to fit in a box hole, and having a slot into which a box hole edge may project, and a separate wedging member adapted to be forced between the connector and the bottom of a box to move the connector laterally with respect to the box hole axis to grip a cable between the exposed box hole edge and connector.
  8. A connector comprising a sleeve adapted to fit in a box hole, and having a slot into which a box hole edge may project, a separate wedging member adapted to be forced between the connector and the bottom of a box to move the connector laterally with respect to the box hole axis to grip a cable between the exposed box hole edge and connector, and said sleeve having a groove in which the wedging member slidably fits.
  9. A connector comprising a sleeve adapted to fit in a box hole, and provided with opposite box wall entry slots into one of which a box hole edge is received to grip against a cable, means including a fork one prong of which slides into one slot and grips against the cable to move it laterally in a box hole and grip said cable aforesaid, and another prong of which passes through the other slot and is adapted to bear against a box wall.
  10. A connector comprising a sleeve adapted to fit in a box hole, and provided with opposite box wall entry slots into one of which a box hole edge is received to grip against a cable, means including a fork one prong of which slides into one slot and grips against the cable to move it laterally in a box hole and grip said cable aforesaid, an-

other prong of which passes through the other slot and is adapted to bear against a box wall, and an abutment flange included on the sleeve adjacent the slots to close a
5 box hole.

In testimony whereof I affix my signature.
